UNITED STATES PATENT OFFICE

104,031

DESIGN FOR A CARPET SWEEPER

Henry W. Gussack, Richmond Hill, N. Y.

Application January 22, 1937, Serial No. 67,246

Term of patent 7 years

To all whom it may concern:

Be it known that I, Henry W. Gussack, a citizen of the United States, residing at Richmond Hill, in the county of Queens and State of New York, have invented a new, original, and ornamental Design for Carpet Sweepers, of which the following is a specification, reference being had to the accompanying drawing, forming part thereof.

Fig. 1 is a plan view showing my new design carpet sweeper with the handle therefor shown in dotted lines, and the casing having two parallel bars of contrasting color to the body of the carpet sweeper.

Fig. 2 is an end view of the carpet sweeper. The handle is shown in a fragmentary condition for convenience of illustration.

I claim:

The ornamental design for a carpet sweeper substantially as shown and described.

HENRY W. GUSSACK.
